UNITED STATES PATENT OFFICE

EMMETT R. SEWARD, OF BRADY, TEXAS

SIDE DITCH SCRAPER FOR DITCHERS

Application filed September 15, 1930. Serial No. 482,066.

This invention relates to ditchers and has for an object to provide side scrapers which may be readily applied to any make ditcher and will operate to scrape back into the ditch the dirt that accumulates on both sides of the ditch from plowing up and overflowing of the buckets.

A further object of the invention is to provide side scrapers which may be swiveled on a vertical axis to any desired angle and which may be shifted laterally on a horizontal pivotal axis whereby the scrapers may be adjusted to any width of ditch.

A still further object is to provide side scrapers which can be adjusted toward or away from the ditcher to conform to the angle of the bucket conveyer in a deep or shallow ditch.

A still further object of the invention is to provide side scrapers which may be elevated so as to be out of the way when not in use.

A still further object is to provide side scrapers which are composed of a few simple, inexpensive and durable parts which will be manufactured at a minimum cost and which may be applied to any make ditcher without alteration to the latter.

With the above and other objects of the invention the invention consists in certain novel details of construction and combination of parts hereinafter fully described and claimed, it being understood that various modifications may be resorted to within the scope of the appended claims without departing from the spirit thereof.

In the accompanying drawings forming part of this specification,

Figure 1 is a fragmentary side elevation of a ditcher equipped with my improved side scrapers,

Fig. 2 is a rear elevation of the ditcher showing the side scrapers in operative position,

Fig. 3 is a detail plan view of one of the

side scrapers and showing the same in dotted lines in an adjusted position on its horizontal pivotal axis,

Fig. 4 is a detail plan view of one of the side scrapers with parts removed and showing the scraper in dotted lines swiveled to an adjusted position on its vertical pivot,

Fig. 5 is a sectional view taken on the line 5—5 of Fig. 4 and showing the adjusting bolt and the vertical pivot bolt of the scraper,

Fig. 6 is a sectional view taken on the line 6—6 of Fig. 5,

Fig. 7 is a detail sectional view showing the hoist, and

Fig. 8 is a detail view showing the hand wheel and ratchet mechanism of the hoist.

Referring now to the drawings in which like characters of reference designate similar parts in the various views, 10 designates the rear portion of a ditcher and 11 the endless conveyer chain which carries the buckets 12 of the ditcher. The ditcher may be any make and forms no part of the present invention.

In carrying out the invention, I provide a pair of curved side scrapers 13, each of which is equipped at the working edge with a cutting blade 14 which preferably is removably secured in position by bolts 15. Each scraper is provided with vertically aligned openings 16, best shown in Fig. 1, and preferably arranged in sets of threes whereby the scraper may be adjusted longitudinally, as will presently appear.

Each scraper is provided with an arcuate angle iron bracket 17, the ends 18 which are bent downwardly and then curved rearwardly, as shown at 19, to lie along the rear face of the scraper. Bolts 20 are passed through said rearwardly curved portions 18 and through a pair of the openings 16. Between the ends 18 of the arcuate bracket an angle iron bracket 21 is positioned and is provided with a curved lower end 22 which is likewise bolted, as shown at 23, to the scrap-

er. It will be observed that the scraper as well as the arcuate bracket 17 and the bracket 21 form a unitary assembly to which the scraper is secured by the bolts 20 and 23, 5 which latter may be selectively engaged in any pair of the openings 16 to adjust the blade longitudinally to adapt it to various widths of ditches.

The scraper assembly depends or hangs 10 from an angle iron supporting bar 24, best shown in Figs. 3 to 5 inclusive. This bar extends parallel with the longitudinal axis of the ditcher, as best shown in Fig. 2. A pivot bolt 25 is passed through the bottom flange of 15 the angle iron bar and through the bent over end of the center bracket 21 of the scraper, as best shown in Figs. 4 and 5. An adjusting bolt 26 is passed through the bottom flange of the angle iron supporting bar and 20 is selectively engaged in any one of a series of openings 27 formed in the arcuate bracket 17, as also best shown in Figs. 4 and 5. The scraper may consequently be swiveled on the vertical pivot bolt 25 to any desired position 25 transversely of the supporting bar 24 and locked in this adjusted position by the adjusting bolt 26, as best shown in Fig. 4.

Referring now more particularly to Fig. 3, it will be seen that a pair of bars 28 and 29 30 are bolted to the upright flange of the angle iron supporting bar 24, as shown at 30 and 31. These bars are provided with eyes 32 and 33 respectively which rotatably receive a horizontal pivot shaft 34. Said pivot shaft at 35 the inner end is bent rearwardly, as shown at 35, and is bolted, as shown at 36, to any convenient part of the ditcher. Furthermore, a pair of brace bars 37 and 38 are secured 40 to the outer end of the pivot shaft, as shown at 39 in Fig. 2, and the forward ends of these brace bars are bolted as shown at 40 and 41 to any convenient part of the ditcher. It will be observed by again referring to Fig. 3 that set screws 42 are passed through the 45 eyes 32. The purpose of these set screws is to permit of the scraper being adjusted laterally on the horizontal pivot shaft 34, as shown in dotted lines in Fig. 3.

There is still another adjustment that may 50 be made to adjust the scraper longitudinally toward or away from the ditcher and by referring to Figs. 1 and 5 it will be seen that the angle iron supporting bar 24 is provided with a plurality of longitudinal slots 43 in 55 the upstanding flange thereof. These slots receive the above described bolts 30 and 31 of the arms 28 and 29. By adjusting the bolts toward the forward ends of the slots, the scraper will be held rearwardly from the 60 rear end of the ditcher and by adjusting the bolts to the rear ends of the slots the scraper will be adjusted to lie closer to the rear end of the ditcher. A more exaggerated adjustment may be obtained, of course, by positioning the bolts in other slots of the line of 65

slots 43 toward the rear end of the bar 24. The purpose of this longitudinal adjustment of the scraper on the supporting bar 24 is to permit of the scraper being positioned to meet the different angles of travel of the buckets 70 for deep or shallow ditches. Of course, when the ditch is deep, the buckets will travel at a more vertical angle, hence closer to the ditcher, and the scraper must therefore be moved to travel closer, and vice versa in case 75 of a shallow ditch.

It will now be seen that each scraper is adjustable in three different ways. First, each scraper may be swiveled on the vertical pivot bolt 25, as shown in Fig. 4, or may be adjusted laterally on the horizontal pivot shaft 34, as shown in Fig. 3, or may be adjusted toward or away from the rear of the ditcher by adjustment of the bolts 24, as is obvious by referring to Fig. 1. An additional adjustment of the scraper transversely of the supporting bar 24 by manipulation of the bolts 20 and 23, Figure 1, is also permitted.

For elevating the scraper, as shown in dotted lines in Fig. 1, when not in use, a hoisting drum 44 is provided with a shaft 45 which is equipped with a hand wheel 46, the shaft being journaled in suitable bearings 47 and 48, Figure 7, which are integral with a 90 bracket 49. The bracket is bolted, as shown at 50 in Figure 3, to a channel iron base plate 51. In Fig. 4 the base plate is shown with the hoisting drum removed and this figure also shows that the base plate is bolted, as 95 shown at 52, to the upright flange of the supporting bar 24 underneath the arm 29.

Referring back to Figure 7, it will be seen that the shaft 45 and the drum 44 are secured together as a unit by a bolt 53. To this bolt is connected the busy end of a cable 54, best shown in Figs. 1 and 2, the same being trained over a sheave 55 carried on the extended end 56, Figure 2, of a shaft 57 which in most cases forms a part of the ditcher, 101 the shaft being supported by channel iron members 58 and 59, best shown in Fig. 1. The cable 54 is connected preferably to an eye bolt 60, which eye bolt is carried by the slotted angle iron supporting bar 24, as best 11 shown in Figs. 1, 3 and 4. Obviously, the cable may be wound upon the drum 44 by means of the hand wheel 46 to elevate the scraper to the position shown in dotted lines in Fig. 1, or lower the scraper to operative 12 position, as shown in full lines in Fig. 1.

By referring to Fig. 8, it will be seen that a ratchet 61 is secured to the drum shaft 45 and is engaged by a dog or pawl 62 carried by a lug 63, Fig. 3, on the bracket 49 to maintain the scraper in either raised or lowered position laterally of the ditcher.

In operation, the scrapers above described are disposed laterally of the bucket conveyer 11 and operate to scrape back into the ditch 12

the dirt which is spilled from the buckets. By adjusting the scrapers toward or away from the ditcher, as above described, or swiveling the scrapers on their vertical pivots, as well as by adjusting the scrapers longitudinally of their supporting brackets 24 by means of the bolts 20, various positions of the scrapers may be obtained to suit various widths and depths of ditches.

Having thus described the invention, I claim:

1. The combination with a ditcher of side scrapers adapted to scrape back into the ditch the dirt spilled by the buckets of the ditcher, and means for adjusting the scrapers laterally toward and away from the ditcher to accommodate the scrapers to various widths of ditches.

2. The combination with a ditcher of side scrapers adapted to scrape back into the ditch the dirt spilled by the buckets of the ditcher, means for adjusting the scrapers on horizontal pivots toward and away from the ditcher to accommodate the scrapers to various widths of ditches, and means for elevating said scrapers on said horizontal pivots when not in use.

3. The combination with a ditcher of side scrapers, a horizontal pivot for each side scraper attached to the ditcher, means for raising and lowering said scrapers on said pivots, and means for adjusting said scrapers on said pivots laterally toward and away from said ditcher to accommodate the scrapers to various widths of ditches.

4. The combination with a ditcher of side scrapers, means pivotally connecting the side scrapers to the ditcher, and means operatively connecting each scraper to the first named means whereby each scraper may be adjusted bodily toward or away from the rear end of the ditcher to accommodate the scrapers to the angular position of the bucket conveyer in deep or shallow ditches.

5. The combination with a ditcher of side scrapers, a supporting bar for each side scraper extending substantially parallel with the axis of the ditcher, means for pivotally connecting each scraper to each supporting bar, means for locking each scraper in various adjusted positions transversely of its pivotal movement on said bar, and means for attaching said bars pivotally to the ditcher.

6. The combination with a ditcher of side scrapers, a supporting bar for each scraper, a horizontal pivot shaft carried by the scraper, bars connected to said supporting bar and having eyes rotatably receiving said pivot shaft, set screws carried by said eyes whereby said supporting bar may be adjusted longitudinally of said pivot shaft, and a hoist operatively connected to said supporting bar for rocking said bar upwardly on said pivot shaft.

7. The combination with a ditcher of a

horizontally disposed pivot shaft extending laterally from the ditcher, a supporting bar pivotally connected to said pivot shaft, a scraper having a vertical pivot operatively connected to said supporting bar intermediate the ends thereof, an arcuate bracket carried by said scraper having a series of openings, an adjusting bolt passed through said supporting bar and one of said openings whereby to hold said scraper at any angular position transversely of said supporting bar, and means for adjustably securing said supporting bar longitudinally of said pivot shaft whereby said scraper may be adjusted bodily transversely of the ditcher.

8. The combination with a ditcher of a side scraper, a supporting bar for the side scraper extending substantially parallel with the longitudinal axis of the ditcher, said supporting bar having a series of longitudinal slots therein, a horizontal pivot shaft carried by the ditcher, bars pivoted on said shaft and extending along said supporting bar, and adjusting bolts passed through the last named bars and said supporting bar for adjusting said scraper bodily toward or away from said ditcher to accommodate the scraper to the angular position of the scraper buckets in deep or shallow ditches.

9. The combination with a ditcher of a side scraper, a supporting bar for the side scraper extending substantially parallel with the longitudinal axis of the ditcher, a pivotal connection between said scraper and said supporting bar whereby said scraper may be adjusted at various angular positions transversely of said bar, a pivot shaft carried by the scraper, bars pivotally connected to said shaft, and means adjustably connecting the free ends of said bars to said supporting bar whereby said supporting bar may be adjusted bodily toward or away from said ditcher.

10. The combination with a ditcher of a scraper, an arcuate bracket connected at the ends to said scraper, a bracket disposed between the ends of said arcuate bracket, a supporting bar extending substantially parallel with the longitudinal axis of the ditcher, a pivotal connection between said centrally disposed bracket and said supporting bar, an adjusting bolt passed through said supporting bar and selectively engageable in a series of openings formed in said arcuate bracket whereby to maintain said scraper in any desired angular position transversely of said supporting bar, and means pivotally securing said supporting bar to said ditcher whereby the scraper may be raised or lowered bodily.

11. The combination with a ditcher of a scraper, a blade attached to the lower end of said scraper, a supporting bar for the scraper extending substantially parallel with the longitudinal axis of the ditcher, a pivotal connection between said supporting bar and said scraper whereby said scraper may be swiveled.

transversely of the supporting bar, an adjusting bolt operatively connected to said supporting bar and to said scraper for holding said scraper in various adjusted positions,
5 a bar pivotally connected to said scraper, and an adjusting bolt passed through the free end of said bar and selectively engageable in a series of longitudinal slots formed in said supporting bar whereby said supporting bar
10 and scraper may be adjusted bodily toward or away from said ditcher.

In testimony whereof I affix my signature.
EMMETT R. SEWARD.
